R. Care,

No 22,781.

Polishing Metals,

Patented Feb. 1, 1859.

Fig. 2

Fig. 1.

UNITED STATES PATENT OFFICE.

REUBEN CAVE, OF LOUISVILLE, KENTUCKY.

MACHINE FOR POLISHING METALS.

Specification of Letters Patent No. 22,781, dated February 1, 1859.

To all whom it may concern:

Be it remembered that I, REUBEN CAVE, of the city of Louisville, in the county of Jefferson and State of Kentucky, have invented a new and useful Improvement in Machinery for Grinding or Polishing Saw-Blades and Knives or Any other Metal Article with a Flat Surface with a Long Bevel; and I do hereby declare that the following is a full, clear, and exact description of the construction and operation of the same and also the improvements, reference being had to the drawing on file in the Patent Office of the United States, which was sent with my application for a patent for said machine, which drawing is made part of this specification for my improvement, in which—

Figure 1 is a side elevation; Fig. 2, an end elevation. Fig. 3 is a plan.

20 F is the frame.

L is a plumber block for bearing the upper stone.

O is a gum spring.

25 A is the upper stone.

A' is the under stone.

B, B, are pulleys.

H, H, are hand wheels.

W, W, are a pair of miter wheels.

30 S, S, are screws by which the upper stone is regulated.

The construction and operation of this machine: Two grind stones running edge to edge opposite ways, one immediately above

the other, and both running at the same time, the upper stone running one-third 35 faster than the under one. The article polished by reason of the upper stone running faster than the other, rests between the stones, without any apparatus to hold it while it is being polished. From two to 40 sixteen, knives one and one-quarter inches wide, or two saws, can be polished at the same time.

The stones are three feet in diameter, and eighteen inches thick, and with two horse 45 power applied, will polish more in one day than twelve men in the ordinary way. The stones are regulated by four screws, and when they get out of order, let the water off, and bring the stones together, they will put 50 themselves in order in a very short time.

I do not claim the running of two polishing grit stones together or running them both at the same time; but

What I claim as my new and useful invention, and improvement, and desire to secure by Letters Patent is—

The running two polishing grit stones edge to edge in opposite directions one immediately above the other (and both running at the same time) the upper stone running faster than the under one.

REUBEN CAVE.

Witnesses:

W. C. WOOD,

R. A. LOGAN.
